Reginald Malcolm Broadhead, Maidenhead, England, assignor to Crown Distillers Limited, London, England

Filed Dec. 27, 1971, Ser. No. 212,874

Claims priority, application Great Britain Nov. 12, 1971

Term of patent 14 years

Int. Cl. D9—01

U.S. Cl. D9—159

FIG. 1.

FIG. 2.

FIG. 3.

FIG. 4.

FIG. 1 is an elevational view of a combined bottle and cap showing my new design, the opposite side being the same in appearance as the side shown;

FIG. 2 is an elevational view looking from the right of FIG. 1 the opposite side being the same in appearance as the side shown;

FIG. 3 is a top plan view; and

FIG. 4 is a bottom plan view thereof.

I claim:

The ornamental design for a combined bottle and cap, as shown and described.
